UNITED STATES PATENT OFFICE

166,183

WALL PLAQUE

Morris E. Goldstein, Denver, Colo.

Application July 21, 1951, Serial No. 15,978

Term of patent 7 years

(Cl. D29—23)

To all whom it may concern:

Be it known that I, Morris E. Goldstein, a citizen of the United States, residing at Denver, State of Colorado, have invented a new, original, and ornamental Design for Wall Plaque, of which the following is a specification, reference being had to the accompanying drawing, forming a part hereof.

I claim:

The ornamental design for a wall plaque, as shown.

MORRIS E. GOLDSTEIN.
